UNITED STATES PATENT OFFICE.

LEO STEIN, OF ROCHESTER, NEW YORK, ASSIGNOR TO THE STEIN MANUFACTURING CO., OF SAME PLACE.

DESIGN FOR A BURIAL-CASKET.

SPECIFICATION forming part of Design No. 18,413, dated June 26, 1888.

Application filed December 19, 1887. Serial No. 258,416. Term of patent 14 years.

To all whom it may concern:

Be it known that I, LEO STEIN, a citizen of the United States, residing at Rochester, in the county of Monroe and State of New York, have invented and produced a new and original Design for Burial-Caskets, of which the following is a specification, reference being had to the accompanying drawings, forming part thereof.

10 Figure 1 is a side elevation of a burial-casket, showing my design in application. Fig. 2 is an enlarged detail side elevation; and Fig. 3, a section of the molding used, giving a clearer idea of the appearance than can be had in the smaller view of Fig. 1.

15 The leading feature of my design consists in a molding formed to represent a connected series of balls, *a*, arranged horizontally in rows near the marginal edges of the top or lid and 20 the upper edge and base of the casket-body, bordered by a straight edge or surface, *b*, on each side.

25 The burial-case *c* is of any desired general outline, and is ornamented by rows of the ball-molding arranged horizontally, as shown in the drawings, near the marginal edges of the

top or lid, upper part of the casket, and the base of the casket, the balls being so closely connected as to present segmentally-curved upper and lower edges and parallel or substantially 30 parallel side edges, presenting a very handsome and rich appearance.

Having thus fully described my design, what I claim as new, and desire to secure by Letters Patent, is—

35 The herein-described design for burial-caskets, consisting of a ball-molding arranged in horizontal rows about the marginal edges of the casket, as shown, the balls so closely connected as to present segmentally-curved upper 40 and lower edges and parallel or substantially parallel side edges, all substantially as shown and described.

45 In testimony whereof I have hereunto signed my name, in the presence of two attesting witnesses, at Rochester, in the county of Monroe, in the State of New York, this 14th day of December, 1887.

LEO STEIN.
